UNITED STATES PATENT OFFICE.

LILE C. RAWSON, OF CHICAGO, ILLINOIS, ASSIGNOR TO E. S. KYLE, OF CHICAGO, ILLINOIS.

PRINTING MACHINE.

Application filed March 10, 1922. Serial No. 542,529.

This invention relates to printing machines, and has special reference to that type of printing machine designed to print upon large flat or plane surfaces such as mat board or other fabricated materials.

An object of the invention is to provide an improved printing machine of the type mentioned including a novel mechanism for operating and controlling the form impression cylinder and the paint applicator so the paint will be applied to the form impression cylinder during travel thereof in one direction but will not be applied thereto during travel thereof in the other direction, so that the movement of the form impression cylinder in one direction is utilized to prime the mat board, etc., which is being printed.

Another object of the invention is to provide a printing machine of the character mentioned, comprising a reciprocating carriage for the form impression cylinder and novel mechanism for reversing direction of travel of the carriage to cause the form impression cylinder to act as a primer during movement thereof in one direction and to complete the operation of printing during a movement or movements thereof in the opposite direction.

Another object of the invention is to provide a printing machine of the character mentioned, in which the operating motor is mounted upon and carried by the carriage of the form impression cylinder.

Another object of the invention is to provide a highly improved transmission mechanism and means for controlling it to operate the carriage in either direction.

Other objects will appear from the following description, reference being made to the drawings in which

Fig. 1 is a top plan view of my improved machine.

Fig. 2 is a side elevation of the machine looking toward the side on which the motor is mounted.

Fig. 3 is a side elevation showing the other side of the machine.

Fig. 4 is a vertical sectional view on the line 4-4 of Fig. 2.

Fig. 5 is an end elevation of the machine, viewed from the left of Fig. 2.

Fig. 6 is a horizontal transverse sectional

view of the transmission mechanism on the line 6-6 of Fig. 7.

Fig. 7 is a vertical transverse sectional view of the transmission mechanism.

Fig. 8 is a vertical sectional view on the line 8-8 of Fig. 7.

Fig. 9 is a view showing one of the clutch devices included in the transmission mechanism.

The table 1 for holding the work during operation of the machine is supported by a frame 2 having ledges 3 on opposite sides thereof. A rail 4 is mounted on one of the ledges 3 and a rail 5, having a pointed or wedge-shaped upper surface, is mounted on the other ledge 3. The rails 4 and 5 are of hard metal, such as rolled steel, and are secured in rigid parallel relationship. 70

A carriage comprising side members 6 and connecting members 7 extending across the machine above the table 1 is provided with rollers 8 arranged to operate upon the rail 4 and with grooved rollers 9 arranged to 75 operate upon the rail 5. Obviously, the grooved rollers 9 operating on the rail 5 will guide the carriage properly in operation.

A bracket 10 is attached to one side of the carriage 6 and a supporting frame 11 is attached to the other side of the carriage. 80

A shaft 12 is journaled in bearings supported by the bracket 10 and by the frame 11. The shaft 12 extends transversely of the machine, parallel with the upper surface of 85 the work table 1. A form impression cylinder 13 is supported by the shaft 12. The impression forms may be secured to the cylinder 13 in any desired manner. After the forms are applied and the work is placed upon the table 1, the carriage is operated in alternately opposite directions, provision being made so that the work is primed during travel of the cylinder in one direction and the printing is completed during travel of 95 the cylinder in the opposite direction.

A motor 14 is supported by the carriage within the frame 11 and operates a shaft 15 extending into and journaled in a housing 16 for the transmission mechanism. A 100 worm 17 on the shaft 15 within the housing meshes with a worm gear 18 loosely mounted upon the shaft 19. The shaft 19 has a pinion 20 (Fig. 2) thereon meshing with one

of two large gears 21 that are rigid with the shaft 12 of the form impression cylinder. The large gears 21 mesh with parallel racks 22 that are rigid with the frame of the machine. It is obvious that if the shaft 19 be rotated in one direction the carriage of the form impression cylinder will be operated toward one end of the machine, and if said shaft 19 be rotated in the opposite direction 10 the carriage will be operated toward the other end of the machine. My invention comprises mechanism for effecting this reverse rotation of the shaft 19 to reverse the travel of the carriage while the motor shaft 15 rotates continuously in one direction.

As stated and as shown, the worm gear wheel 18 is loosely supported upon the shaft 19. The worm gear 18 is rigid with a gear wheel 23 that meshes permanently with a gear 20 wheel 24 (Fig. 7) attached to a shaft 25. By this gearing the shaft 25 is rotated whenever the motor operates. The transmission mechanism includes means for clutching the worm gear 18 upon the shaft 19 to rotate 25 said shaft 19 in one direction; and also includes means whereby the shaft 19 may be rotated in the opposite direction from the shaft 25. I will first describe the clutch device for clutching the worm gear 18 to the 30 shaft 19.

As shown (Fig. 6), a drum or sleeve 26 is attached to worm wheel 18 and the gear wheel 23 by bolts 26^a. Inside the drum or sleeve 26 but disconnected therefrom a hub 35 27 is keyed to the shaft 19 and has radial arms 28. An arcuate arm 29 is in connection with the outer end of each of the arms 28. A shoe 30 is located between each of the curved arms 29 and the lining 31 of the 40 drum 26. The shoes 30 are movable to and from position to form a clutch connection between the curved arms 29 and the drum 26 in order to rotate the shaft 19. Springs 32 draw the shoes 30 from clutching position, 45 leaving the drum 26 free to rotate without rotating the shaft 19. Mechanism is provided for actuating the shoes 30 to position to form a clutching connection between the drum 26 and the arms 29 so as to rotate the shaft 19. As shown a pair of arms 33 50 (Figs. 6 and 9) are pivotally supported by the hub 27 and have their outer ends extending under levers 34. The levers 34 are pivotally supported against pins 35 mounted in matching recesses in the ends of the shoes 30 and in said levers 34. The pins 35 are not rigid with any part, but are wholly supported by the shoes 30 and the levers 34. The outer ends of the levers 34 extend 55 60 against the ends of the shoes 30 so that by moving the inner ends of the levers 34 radially outward the shoes 30 will be forced against the tension of the springs 32 to engage projections 36 on said shoes with the 65 ends of the curved arms 29, while the ad-

jacent end of the other shoe is forced outwardly by the pressure of the lever 34 against the pin or pivot 35. Referring to Fig. 9, it will be understood that this operation is obtained as follows: The outward movement of the inner end of each lever 34 causes its pin 35 to force outwardly the shoe 30, which said pin engages, against the lining 31. At the same time, each lever 34 forces the other shoe 30 around until its 70 projection 36 engages the end of the arm 34. Due to their relationship, firm engagement of the shoes 30 with the lining 31 and the projections 36 with the arms 29 is obtained when all of said parts are moved as aforesaid. In this way the clutch is closed and the shaft 19 will be rotated by the drum 26.

A frame 37 is supported within the housing 16 by a pair of collars 38 and 39. The collar 38 has a beveled portion 40 movable under the outer ends of the arms 33 a sufficient distance to engage the ends of said arms in a groove 41 around said collar. The parts are shown so positioned in Fig. 6. When in the position there shown, the clutch above described is closed and the shaft 19 is rotated thereby. By shifting the clutch closer 38 in the opposite direction, that is away from and out of engagement with the arms 33, the clutch will be opened and the drum 26 may turn freely without operating the shaft 19. Screws 42 in the levers 34 are settable to bear against the arms 33 so as to vary the adjustment of the parts.

From the foregoing it will be seen that by setting the clutch just described in the position shown in Fig. 6, the shaft 19 will be rotated from the gear supported thereby. By opening the clutch above described the 105 worm gear 18 will be left free to turn on the shaft 19. Provision is made for driving the shaft 19 from the shaft 25. As shown (Fig. 7), a sprocket wheel 43 on the shaft 25 is connected with a sprocket wheel 44 loose on the shaft 19 by a sprocket chain 45. Obviously, if the sprocket wheel 44 be clutched to the shaft 19 when the clutch above described is open, the shaft 19 will be rotated from the shaft 25.

The sprocket wheel 44 is in connection with a drum 46 loose on the shaft 19 and equipped with a clutch mechanism just like the clutch mechanism above described, the parts being of like construction and having the same reference numerals applied thereto. The arms 33 of the clutch for the sprocket wheel 44 are movable radially outward by an inclined extension 47 in connection with the collar 39, and having a groove 48 corresponding to the groove 41. The frame 37 which connects the collars 38 and 39 is operable to open one clutch automatically and as an incident to the closing of the other clutch.

The invention includes means for shifting the frame 37 automatically and as an incident to the approach of the carriage toward each end of its movement and said means will now be described.

One end of the housing 16 pivotally supports a bell crank lever 49, one arm of which is above a vertically movable plunger 50. A cam 51 on the frame of the machine is in the path of movement of the plunger 50 so that as the carriage approaches the end of the frame the plunger 50 will be raised, thereby operating the lever 49. The lever 49 is connected by a link 51^a (Fig. 4) with an arm 52 attached to a rod 53 supported for rocking movements in the housing 16. Arms 54 attached to the rod 53 inside the housing are pivoted to the frame 37 and operate to shift the frame to position to close the clutch in direct connection with the worm gear 18 and to open the other clutch in connection with the sprocket wheel 44. Assuming that the carriage is moving toward the right, as seen in Fig. 2, the raising of the plunger 50 by the cam 51 will shift the clutch mechanism to reverse direction of rotation of the shaft 19 and thereby reverse the direction of travel of the carriage. As the carriage approaches the other end of the frame, a plunger 55, similar to the plunger 50, rides upon a cam block 56 (Fig. 2) raising an arm 57 attached to the other end of the rod 53, thereby causing the arms 54 (Fig. 8) on said rod 53 to shift the frame 37 to position to open the clutch controlling the worm gear 18 and to close the clutch in connection with the sprocket wheel 44 and again reverse the direction of travel of the carriage.

The bracket 10 has an arm 58 (Fig. 3) and the frame 11 has a similar arm 59 (Fig. 2). A shaft 60 is rotatively supported in bearings on the arms 58 and 59 and has a gear 61 (Fig. 1) meshing with one of the form impression cylinder gears 21. The gear 61 is arranged on the shaft 60 so that rotation of said gear in one direction will rotate the shaft 60, but rotation of said gear in the opposite direction will not rotate the shaft 60. A sprocket wheel 62 is attached to the shaft 60 (Fig. 3) and is engaged by a chain 63 which also passes around a sprocket wheel 64. The sprocket wheel 64 is attached to a shaft 65 which is journaled for rotation in the end walls of a paint basin 66. The paint basin 66 is supported by arms 67 swinging from the shaft 60. A paint applying roller 68 (Figs. 1 and 5) is mounted on the shaft 65 and operates within the basin 66 effectively to take paint from the basin and apply it to the forms on the impression cylinder. Another roller 69 is supported above the roller 68 so as to operate against the latter and prevent excessive amounts of paint from being placed on the forms. Look-

ing at Fig. 3 and assuming that the carriage is moving toward the right, it will be seen that the shaft 65 and the roller 68 thereon are rotated in a counter-clockwise direction. The roller 68 takes paint from the basin 66 and the excessive amount of paint is removed or distributed by the roller 69 before the paint reaches the forms. By this arrangement the paint applicator places only the desired amount of paint on the form.

Still looking at Fig. 3, paint will be applied to forms on the impression cylinder only during movement of the carriage toward the right. On the reverse movement of the carriage, that is during movement of the carriage toward the left, as seen in Fig. 3, the paint applicator is rendered ineffective so that it does not apply paint to the form impression cylinder, leaving the leftward movement of the carriage, as seen in Fig. 3, to function for priming the mat board. That is, the relatively small amount of paint remaining on the forms after the completion of the movement of the carriage toward the right is utilized to prime a new mat board placed on the supporting table 1. Movement of the carriage in one direction is thus utilized to apply a priming coat of paint to the mat board, and the movement of the carriage in the opposite direction is utilized to apply a finishing coat of paint to the mat board that had been primed. Thus, a round trip or complete cycle of movement of the carriage completes the work on the form on a sheet of mat board.

A friction device 70 on the shaft 12 (Figs. 1 and 3) has a link 71 pivoted thereto, the opposite end of said link being pivoted to an arm 72 on a shaft 73 supported by the carriage 6. The device 70 is a half ring mounted on the shaft 12 and frictionally engaging said shaft. Said half ring may be held in frictional engagement with the shaft 12 by being bolted to a cooperating ring member, as shown. As a result of the frictional contact of the part 70 with the rotary shaft 12 there is a tendency to turn the part 70 with the shaft. A collar 74 has one end connected to the arm 72 by a pivot 74^a and the opposite end receiving the threaded end of a rod 75 rotatively mounted in a bearing 76 swiveled on the basin 66. The rod 75 is held from endwise movement through a bearing 76 by collars 75^a rigid with the rod on opposite sides of said bearing 76. The fact that the bearing 76 is swiveled permits the sleeve 74 to raise and lower the connected end of the rod 75 in moving the paint applying device toward and away from the impression cylinder. By this arrangement rotation of the shaft 12 during movement of the carriage toward the right, as seen in Fig. 3, causes the roller 68 to operate against the forms on the cylinder; and reverse movement of the carriage

reversing the rotation of the shaft 12 causes the connection to move the paint applicator roller 68 out of contact with the forms on the impression cylinder, leaving the impression cylinder free to operate as a priming device.

The table 1 is adjustably supported on the upper ends of screws 77 (Fig. 4) so that said table may be adjusted for different 10 thicknesses of material.

From the foregoing it will be seen that my invention is a perfected machine, capable of use for printing artistic designs. The machine is a self-contained mechanism 15 in that the motor is mounted directly upon the machine and is carried with the carriage that is operated thereby. The capability of the machine to perform the work of priming as well as finishing the printing 20 is a distinct advantage.

I am aware that the construction and arrangement may be varied in numerous respects without departure from the nature and principle of the invention.

25 I do not restrict myself unessentially but what I claim and desire to secure by Letters Patent is:—

1. A machine of the character described comprising a work support, a carriage mounted adjacent to said support, a form cylinder supported by the carriage, gearing for moving the carriage and rotating the cylinder, a motor supported by the carriage, mechanism driven by the motor for operating said 30 gearing to move the carriage and rotate the cylinder, and means supported by the carriage for causing said motor to operate said mechanism alternately in opposite directions.

2. A machine of the character described 40 comprising a table for supporting the work, a carriage supported adjacent to the table, a form cylinder supported by the carriage, a motor mounted on the carriage, gearing for moving the carriage and rotating the cylinder, mechanism driven by the motor for operating said gearing, and means supported by the carriage for changing the direction of 45 operation of said mechanism by said motor while said motor operates continuously in one direction.

3. A machine of the character described 55 comprising a table for supporting the work, a carriage supported adjacent to the table, a form cylinder supported by the carriage, a motor mounted on the carriage, gearing for moving the carriage and rotating the cylinder, mechanism driven by the motor for operating said gearing, means supported by the carriage for changing the direction 60 of operation of said mechanism by said motor while said motor operates continuously in one direction, and devices for operating said means to reverse the operation of said mechanism as aforesaid.

65 4. A machine of the character described

comprising a table for supporting the work, a carriage supported adjacent to the table, a form cylinder supported by the carriage, gearing for moving the carriage and rotating the cylinder, a motor mounted on the carriage, mechanism driven by the motor for operating said gearing, devices supported by the carriage for changing the direction of operation of said mechanism by said motor while said motor operates continuously 70 in one direction to move the carriage alternately in opposite directions and to rotate the cylinder alternately in opposite directions, and means operated by said gearing for applying paint to the forms on said cylinder.

5. A machine of the character described comprising a table for supporting the work, a carriage supported adjacent to the table, a paint applying device in said carriage, a motor carried by said carriage, mechanism mounted on the carriage and operated by the motor for moving the carriage back and forth adjacent to the table according to the direction of operation of said mechanism 85 by said motor, and means supported by the carriage for changing the direction of operation of said mechanism by said motor while said motor operates continuously in one direction.

95 6. A machine of the character described comprising a table for supporting the work, a carriage supported adjacent to the table, a paint applying device in said carriage, a motor carried by said carriage, mechanism mounted on the carriage and operated by the motor for moving the carriage back and forth adjacent to the table according to the direction of operation of said mechanism by 100 said motor, means supported by the carriage for changing the direction of operation of said mechanism by said motor while said motor operates continuously in one direction, and means for moving said paint applying device to and from operative position.

105 7. A machine of the character described comprising a table for supporting the work, a carriage supported adjacent to the table, a paint applying device in said carriage, a motor carried by said carriage, mechanism mounted on the carriage and operated by the motor for moving the carriage back and forth adjacent to the table according to the direction of operation of said mechanism by 110 said motor, means supported by the carriage for changing the direction of operation of said mechanism by said motor while said motor operates continuously in one direction, and means for holding the paint applying device in operative position during movement of the carriage in one direction and out of operative position during movement of the carriage in the opposite direction.

115 8. A machine of the character described

comprising a table for supporting the work, a carriage supported adjacent to the table, a form cylinder supported by the carriage, a motor supported by the carriage, mechanism driven by the motor for operating the carriage and rotating the cylinder alternately in each of two directions, devices supported by the carriage for changing the direction of operation of said mechanism by said motor while said motor operates continuously in one direction, a paint applying device supported in said carriage for supplying paint to the forms on the cylinder, and mechanism for operating said paint applying device as an incident to the operation of the carriage.

9. A machine of the character described comprising a table for supporting the work, a carriage supported adjacent to the table, a form cylinder supported by the carriage, a motor supported by the carriage, mechanism driven by the motor for operating the carriage and rotating the cylinder alternately in each of two directions, devices supported by the carriage for changing the direction of operation of said mechanism by said motor while said motor operates continuously in one direction, a paint applying device supported in said carriage for supplying paint to the forms on the cylinder, and means controlling said paint applying device to apply paint to the forms on said cylinder during movement of the cylinder in one direction and to remain ineffective during movement of the cylinder in the other direction, leaving the cylinder to act as a priming device for work during movement of said cylinder in said other direction.

10. A machine of the character described comprising a table for supporting the work, impression mechanism for operating upon the work, a carriage supporting the impression mechanism, driving mechanism mounted on the carriage for operating the carriage in opposite directions and for operating the impression mechanism, a motor for driving said driving mechanism, and means supported by the carriage for reversing the direction of operation of said driving mechanism by said motor while said motor operates continuously in one direction.

11. In a machine of the character de-

scribed, a carriage, a form cylinder supported by the carriage, a shaft supported by the carriage and arranged to rotate continuously in one direction, an additional shaft supported by the carriage, mechanism for rotating the additional shaft alternately in opposite directions, and mechanism driven by the additional shaft for rotating the form cylinder.

12. In a machine of the character described, a carriage, a form cylinder supported by the carriage, a shaft supported by the carriage and arranged to rotate continuously in one direction, an additional shaft supported by the carriage, mechanism for rotating the additional shaft alternately in opposite directions, mechanism driven by the additional shaft for rotating the form cylinder, and means for moving the carriage as an incident to the rotation of said cylinder.

13. A machine of the character described comprising a form cylinder, a movable carriage in which said cylinder is mounted, mechanism for operating and controlling the form cylinder to prime the work with a thin coat of paint by movement of the form cylinder in one direction and complete the work by applying a finishing coat of paint by movement of the form cylinder in the other direction, a prime mover supported by the carriage for operating said mechanism, devices supported by the carriage for changing the direction of operating of said mechanism by said prime mover, and elements for operating said devices automatically and as an incident to the movement of the carriage to a predetermined point.

14. A machine of the character described comprising a carriage, a cylinder supported by the carriage, gearing for moving the carriage and rotating the cylinder, a motor supported by the carriage, mechanism driven by the motor for operating the gearing to move the carriage and rotate the cylinder, devices supported by the carriage for causing said motor to operate said mechanism alternately in opposite directions, and means for automatically operating said devices to cause said motor to operate said mechanism alternately in opposite directions as aforesaid.

LILE C. RAWSON.
